UNITED STATES PATENT OFFICE.

JOSEPH FAUSSE, OF BROCKTON, MASSACHUSETTS, ASSIGNOR TO UNITED SHOE MACHINERY COMPANY, OF PATERSON, NEW JERSEY, A CORPORATION OF NEW JERSEY.

REBOUND CONTROL FOR LASTING-MACHINES.

1,113,764.

Specification of Letters Patent.

Patented Oct. 13, 1914.

Application filed December 30, 1910. Serial No. 600,073.

To all whom it may concern:

Be it known that I, JOSEPH FAUSSE, a citizen of the United States, residing at Brockton, in the county of Plymouth and State 5 of Massachusetts, have invented certain Improvements in Rebound Control for Lasting-Machines, of which the following description, in connection with the accompanying drawings, is a specification, like reference characters on the drawings indicating 10 like parts in the several figures.

This invention relates to Lasting machines and particularly to the type of "bed" lasters which is exemplified in United States 15 Letters Patent No. 1,018,477, granted Feb. 27, 1912, Brock. Such machines have a sliding carriage that supports the heel lasting mechanism and which, for each lasting operation, is moved forwardly from a re- 20 tracted position in which it allows the application of the shoe to the machine. In the forward position it is retained by a catch during the lasting operation and then is automatically released. During the lasting 25 operation a spring is put under compression for closing the heel embracing band and this spring is arranged to force backwardly the heel lasting carriage when the carriage is released, thus opening the machine for the removal of the lasted shoe. 30 It has been found that in order to serve its purpose in the lasting operation on the heavier grades of shoes the spring must be of such a strength that the heel lasting carriage is moved backwardly by it with objectionable force and sometimes it rebounds and comes forward again to a position to obstruct the operator or to cause damage to the shoe.

40 The object of this invention is to overcome this difficulty.

An important feature of this invention consists in provision for retarding the last portion of the backward movement of the carriage and preventing objectionable rebounds. In the illustrated embodiment of 45 this invention the carriage has yieldingly mounted thereon a finger or projection and the frame, or a member carried by the 50 frame, has a socket block to receive the finger as the carriage comes back. In this socket is a spring pressed friction-plug that engages the finger and not only retards the final portion of the rearward movement 55 of the carriage but presses against the fin-

ger and prevents the rebound of the carriage. The spring mounting for the finger takes up the slack as the carriage comes back and furnishes enough rebound force to start the finger forwardly out of engagement with the plug. The friction plug is adjusted in the socket block to give only sufficient resistance to accomplish the desired purpose without holding the carriage back to add a load to the operator's work in advancing the heel lasting mechanism for the next operation.

This invention will now be explained in connection with the accompanying drawings and will then be pointed out in the claims.

Figure 1 is a rear side elevation of so much of a machine of the type referred to as is necessary to a clear understanding of the invention. Fig. 2 shows the socket block, partly in section.

The heel lasting carriage 2 carrying the usual lasting devices slides forwardly and backwardly on the frame 4, which has a track for the anti-friction rollers 5.

In operation the carriage is locked in its forward position by the latch 6 which is fast on a rock shaft 8, that has an arm 10 which overlies a tripper 12 which releases said carriage.

The machine has a cam 30 which through suitable connections actuates a rocker 28 and a lever 25 which is pivoted at 27 and is connected at its upper end through a spring 24 with the heel band closing mechanism all as more fully described in said patent. The cam 30 continues to maintain the spring 24 under tension after the latch 6 is released and the reaction of said spring then causes the lever to fulcrum against the rocker 28 and "kick" the carriage to the left in Fig. 1. On the rear side of the carriage is mounted yieldingly by spring 14 a rod or finger 18, the finger having a collar 19 against which the spring presses to hold the finger projected rearwardly. The frame supports by a clamping bolt 32 a block 35 in which is formed a socket located in alinement with the finger or rod 18 and of about the same diameter. The block is also bored vertically to form a socket which contains a friction plug 34, a spring 36 and an adjusting screw 40. The plug 34 projects far enough into the finger socket so as to engage the finger 18 frictionally and the screw 40 adjusts the tension of the spring 36.

When the carriage is released by means of the tripper 12, which is raised by the cam 38 to lift the latch 6, the heel carriage is forced toward the left in Fig. 1 by the contraction of the spring 24. As the carriage approaches the limit of its movement the finger 18 enters the socket block 35 and has its movement checked as it slides under the spring pressed plug 34. Then the reaction 10 of the finger spring 14, which has been compressed as the backward movement of the carriage was checked, reverses the movement of the heel carriage and presses it forward enough to free or substantially to free 15 the finger 18 from the socket block so that the carriage comes to rest without objectionable shock or rebound.

Having explained my invention I claim as new and desire to secure by Letters Patent 20 of the United States:—

1. In a machine of the class described, the combination with a heel lasting carriage and a slideway therefor, of means acting to move said carriage along the slideway, a finger on the carriage, a socket block on the slideway formed to receive the finger, and means for engaging the finger and arresting it by sliding friction while it is in the socket block, the finger and block being constructed and arranged to continue the friction throughout the possible movement of the finger into the socket block.

2. In a machine of the class described, the combination with a heel lasting carriage and 35 means for automatically moving it rearwardly after the lasting operation, of a finger projecting rearwardly therefrom, and means for slidingly engaging said finger as the carriage approaches the end of said

movement and continuing in engagement 40 therewith to the end of the possible rearward movement of the carriage gradually stopping such movement and resisting return movement of the finger to prevent rebound of the carriage.

3. In a machine of the class described, the combination with a heel lasting carriage and means for automatically moving it rearwardly after the lasting operation, of a finger projecting rearwardly therefrom, a 50 device in contact with said finger slides during the last portion of the rearward movement of the carriage and which checks said movement, a spring compressed by the resistance encountered by said finger and arranged to react to move the carriage forwardly to free the pin from said device.

4. In a machine of the class described, the combination with a heel lasting carriage and means for automatically moving it rearwardly after the lasting operation, of a finger 60 28 and a spring 14 yieldingly projecting the finger from the carriage, a socket block 35 having in its front end a socket to receive the finger and a friction plug 36 65 projecting into the socket to engage the finger to resist both rearward movement of the finger and then forward movement thereof when the spring 14 reacts, substantially as described.

In testimony whereof I have signed my name to this specification in the presence of two subscribing witnesses.

JOSEPH FAUSSE.

Corrections in Letters Patent No. 1,113,764.

It is hereby certified that in Letters Patent No. 1,113,764, granted October 13, 1914, upon the application of Joseph Fausse, of Brockton, Massachusetts, for an improvement in "Rebound Control for Lasting-Machines," errors appear in the printed specification requiring correction as follows: Page 2, line 51, after the word "with" insert the word *which*; same page, line 54, after the comma following the word "movement" insert the word *and*; and that the said Letters Patent should be read with these corrections therein that the same may conform to the record of the case in the Patent Office.

Signed and sealed this 26th day of January, A. D., 1915.

[SEAL.]

R. F. WHITEHEAD,

Acting Commissioner of Patents.
